UNITED STATES PATENT OFFICE.

HENRY F. LINDEROTH, OF CHICAGO, ILLINOIS.

FIRE APPLIANCE FOR PREVENTING OBSTRUCTION OF RAILWAY TRACKS.

Application filed December 26, 1919, Serial No. 347,441. Renewed September 12, 1922. Serial No. 537,849.

To all whom it may concern:

Be it known that I, HENRY F. LINDEROTH, a citizen of the United States, residing at Chicago, in the county of Cook and State of Illinois, have invented a certain new and useful Improvement in Fire Appliances for Preventing Obstruction of Railway Tracks, of which the following is a specification.

This invention relates to fire appliances for preventing obstruction of railway tracks, and has for its object to provide a new and improved device of this description. In cities when fires occur on or near streets having street cars, it is necessary under the conditions usually existing to run the fire hose across these tracks and this stops the running of the street cars and also stops the other traffic on this street. This is a serious inconvenience to the street car company and to the city and is also expensive, for it stops for the time being the income of the street car line and yet the pay of street car employees must continue. This may happen at the very rush hours of the day, in which event the loss to the company and the inconvenience to the city and the general public is very great.

My invention has among other objects to provide means for preventing these evils. Referring now to the accompanying drawings,

Fig. 1 is a plan view showing one form of device embodying the invention;

Fig. 2 is an enlarged sectional view taken on line 2—2 of Fig. 1;

Fig. 3 is an enlarged sectional view showing a modified construction;

Fig. 4 is a sectional view taken on line 4—4 of Fig. 3;

Fig. 5 is a plan view of the device shown in Fig. 4.

Like numerals refer to like parts throughout the several figures.

In carrying out my invention I provide means for conducting the water from the fire engine, under the track. In Figs. 1 and 2 I have shown one form of construction for this purpose. In this construction I provide one or more pipes or conduits 1, 1^a, 1^b, 1^c etc., which extend under the tracks 2. These conduits are preferably permanently placed in position either when the track is made or afterwards. These conduits may be iron pipes and are arranged under the track so as to cross under the same, their ends being bent upwardly as

illustrated so that the hose may be connected therewith. If the pipes are placed in position after the track has been laid, a trench or excavation is made under the track and the pipe or pipes laid therein. In this event I may divide the pipes into two or more sections, the sections being coupled together by suitable couplings 3. By this construction the amount of excavating may be reduced, and I may easily put the sections in place and connect them together. If the device is put in position at the time the track is laid, each pipe may be of one piece if desired. The ends of the pipes in this construction are left open and are provided with suitable means, such as threads 4 for connecting the fire hose thereto. When a fire occurs the fire engine 5 may be moved into proximity to the hydrant or water outlet 6 and connected therewith by the pipe 7 and then a short piece of hose 8 may run from the fire engine to one of the conduits 1. The long fire hose may then be connected to the other end of the conduit and the hose unwound so as to be used at any distant point desired. It will thus be seen that these connections can be made without any obstruction or delay whatever to the traffic, that the cars can continually run over the tracks and that the vehicle traffic can also run over the tracks at all times.

This construction also enables the fire department to use small sections of hose for connecting the engines to the conduits. These small sections of hose, for example, may be made by cutting up into proper lengths the long hose which has been injured so that it cannot be used for long stretches. This secures a large saving to the fire department.

In Fig. 3 I have shown a construction where one conduit or pipe 10 is shown extending under the tracks. The ends of this conduit or pipe are open and are provided with the casings 11, one at each end. These casings are preferably divided into two sections by the wall 12. The conduit 10 connects with the lower section of each casing, the walls provided with a series of openings having threaded nipples 13 to which the hose 9 may be connected. It will thus be seen that any desired number of these nipples may be used so that any desired number of lines of hose can be used with the conduit 10. These nipples are provided with threaded caps 14, and when it is desired to con-

nect the hose thereto, the threaded cap is removed. These threaded caps prevent the water from passing through any of the nipples not connected with the hose. I prefer to provide a cover 15 for each casing, the cover being flush with the street surface.

When it is desired to connect up the engine and the long fire hose, it is only necessary to open or remove the cover and then 10 attach the hose.

I claim:

1. A fire appliance for preventing the obstruction of railway tracks comprising a rigid pipe separate from the water system 15 and from said railway track, said pipe made up in sections and adapted to be placed under the railway track after the track is in position by excavating thereunder, the end sections of said pipe being bent upwardly 20 so as to be in proximity to the rails of the track, boxes connected with the ends of said pipe and having their tops substantially flush with the surface of the street, said boxes provided with a wall intermediate 25 their top and bottom, the pipes being connected to the boxes below the wall, said walls having openings therethrough, and means associated with said openings for connecting a hose thereto and covers for covering said boxes when the hose is not being used.

2. A fire appliance for preventing the obstruction of railway tracks comprising a movable fire engine, means for connecting said fire engine with a source of water supply, a plurality of fixed conduits separate from the water system and the track extending under the railway track, said conduits made in separated sections and removably 40 connected together, the ends thereof being bent upwardly so as to be near the surface of the street, boxes into which the ends of said conduits project, said boxes provided with covers and the tops of said boxes being substantially flush with the surface of the street and in proximity to the rails of said track, means for connecting one end of one or more of said conduits to the movable fire engine after said engine has been brought 50 in proximity thereto, means for connecting the fire hose to the other end of said conduit or conduits, and means for connecting said fire engine with a source of water supply, whereby the water can be forced under the track through said fire hose without interfering with the traffic on the railway.

3. A fire appliance for preventing the obstruction of railway tracks comprising a rigid pipe permanently fixed in position under the track, said pipe separate from the water system and the track and in separable sections so that it may be placed in position by forming an excavation under the track after said track is in place, means at one end 60 of said rigid pipe for attaching thereto a

short piece of hose connected with the fire engine, and means at the other end of said rigid pipe for attaching thereto the long hose having the nozzle through which the water is discharged, whereby water can be forced under the track and through said long hose without interfering with the traffic on the railway.

4. A fire appliance for preventing the obstruction of railway tracks comprising a rigid pipe permanently fixed in position under the track, said pipe separate from the water system and the track and in separable sections so that it may be placed in position by forming an excavation under the track after said track is in place and having its ends bent upwardly so as to be near the surface of the street, boxes into which the ends of said pipes project, said pipe separate from the water system and the track, the tops of said boxes being substantially flush with the surface of the street and in proximity to the track, means at one end of said rigid pipe for attaching thereto a short piece of hose connected with the fire engine, and means at the other end of said rigid pipe for attaching thereto the long hose having the nozzle through which the water is discharged, whereby water can be forced under the track and through said long hose without interfering with the traffic on the railway.

5. A fire appliance for preventing the obstruction of railway tracks comprising a rigid pipe permanently fixed in position under the track, said pipe separate from the water system and the track and in separable sections so that it may be placed in position by forming an excavation under the track after said track is in place and having its ends bent upwardly so as to be near the surface of the street, boxes into which the ends of said pipes project, said pipe separate from the water system and the track, the tops of said boxes being substantially flush with the surface of the street and in proximity to the track, means at one end of said rigid pipe for attaching thereto a short piece of hose connected with the fire engine, and means at the other end of said rigid pipe for attaching thereto the long hose having the nozzle through which the water is discharged, whereby water can be forced under the track and through said long hose without interfering with the traffic on the railway, the upwardly turned ends of said pipes being normally open, casings surrounding said ends, and covers for said casings.

6. A fire appliance for preventing the obstruction of railway tracks comprising a rigid pipe extending under the tracks and having portions thereof extending upwardly to the surface of the street in proximity to said track, said pipe separate from the water system and disconnected from

the track and made up in separable sections removably connected together whereby it may be placed under the track when the track is in position by simply excavating a place therefor under said track, and means for connecting said portions with a fire hose and a fire engine and boxes with which the end portions of said pipes are connected, the

connection between the fire hose and the pipes being inside of said boxes, and a removable cover for each of said boxes substantially flush with the surface of the street. ¹⁰

In testimony whereof, I affix my signature this 6th day of December, 1919.

HENRY F. LINDEROTH.
